UNITED STATES PATENT OFFICE.

GEORGE R. BAILEY, OF BROOKLYN, NEW YORK, ASSIGNOR TO STERLING CASKET HARDWARE COMPANY, OF BROOKLYN, NEW YORK, A CORPORATION OF NEW YORK.

DESIGN FOR A CASKET-HANDLE AND LUGS.

45,583.

Specification for Design.

Patented Apr. 14, 1914.

Application filed February 7, 1914. Serial No. 817,363. Term of patent 7 years.

To all whom it may concern:

Be it known that I, GEORGE R. BAILEY, a citizen of the United States, residing at No. 502 Bedford avenue, Brooklyn, county of Kings, and State of New York, have invented a new, original, and ornamental Design for a Casket-Handle and Lugs, of which the following is a specification, reference being had to the accompanying drawing, forming part thereof.

The figure is a plan view of a casket handle and lugs showing my new design.

I claim:

The ornamental design for a casket handle and lugs as shown.

GEORGE R. BAILEY.

Witnesses:

WALTER B. RAYMOND,
J. J. CAMPBELL.
